HYDROCARBON MOTOR

Filed August 7, 1917 2 Sheets-Sheet 2

Patented May 11, 1926.

1,583,959

UNITED STATES PATENT OFFICE.

HAROLD D. CHURCH, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed August 7, 1917. Serial No. 184,984.

This invention relates to motor vehicles and more particularly to the means for controlling the throttle valve and mixture of the carburetor. In constructions as heretofore made it has been the practice to provide both a hand and foot operated means for controlling the throttle valve, either of which can be actuated independently of the other. In certain classes of vehicles however, it is desirable to provide the pedal means only. This invention is concerned with this latter class and consists in the combination with a pedal, of a hand device operative on the pedal to hold open the throttle valve when the operator desires to crank or start the motor. Another feature resides in the combination with the aforesaid pedal and hand device, of means actuated by said hand device for operating the choke valve of the carburetor so that when the throttle valve is opened by the hand device, the choke valve is simultaneously closed. A further feature consists in the provision of another and independent means for closing the choke valve. Other features of the invention will be apparent from the description taken in connection with the drawings, in which:—

Fig. 1 as a sectional view through a portion of a motor vehicle showing a carburetor controlling device constructed in accordance with this invention, and

Fig. 2 is a perspective view of a carburetor and the apparatus for controlling the same.

Referring to the drawings which show one embodiment of the invention, 10 indicates a hydrocarbon engine having a carburetor 11 including a throttle valve 12 which controls the explosive mixture supplied to the engine and a choke valve 13 which controls the amount of air supplied to the carburetor. The throttle valve 12 is pivotally mounted in the carburetor and is provided with the arm 14 by means of which the valve may be turned. For the purpose of actuating the valve a single means is provided which includes a pedal 15 pivotally mounted at 16 to the floor board 17 of the front of the body of the vehicle. This pedal is formed with a foot pad 18 at one end thereof and the other end is bent to provide an upwardly extending portion 19 which by means of the link 20 is connected to the arm 14 of the throttle valve. It will thus be apparent that when the pad 18 is depressed the throttle valve will be moved in

a direction to open the same. In order to close the valve the pedal 15 may be provided with a lug 21 and a contractile spring 22 interposed between the same and the floor board 17. Adjacent the bent up portion 19 the pedal is provided with a bolt 23 threaded through the same which may be locked in any adjusted position by means of the lock nut 24.

As the throttle valve is automatically held in substantially closed position it is desirable to provide a means for holding it open when the motor vehicle operator is cranking the motor. For this purpose a hand device is provided which is operative on the pedal to hold the same with the throttle valve in any desired open position. This device comprises a rock shaft 25 having its axis parallel with the pivot of the pedal and extending on both sides of the pedal. Immediately under the pedal and adapted to act on the end of the bolt 23 is a cam 26 carried by said shaft 25. At one end the shaft has connected thereto for rotation therewith an arm 27 which by means of a link 28 is connected to a hand lever 29 pivoted at 30 to the dash 31 of the vehicle. This lever is adapted to be held in any position by means of a suitable yieldable locking means, the type shown consisting of the serrated segment 32 carried by the dash and a co-operating pin 33 on the lever. It will be apparent that when the forward end of the hand lever 29 is raised the cam 26 will be rotated in a direction to raise the bolt 23 which through the connections to the throttle valve will move the latter in an opening direction. As the hand device holds the throttle in this open position sufficient mixture will be admitted to the motor so that it may be started and will operate at a speed so that it will warm up quickly. Because of the loose connection between the pedal and the hand device it will be seen that the pedal may be depressed as desired and that the hand device merely limits the extent of the closing movement of the same.

In starting a motor, in addition to providing means for holding the throttle valve slightly open, it is also desirable to close or choke the air intake of the carburetor so that a very rich mixture will be supplied to the engine. For this purpose the rock shaft 25 at the end opposite the arm 27 loosely carries an arm 34 which is yieldingly con-

nected to the rock shaft by means of a coil spring 35, one end of which is secured to the shaft and the other of which is fastened to the arm. The end of the arm 34 is connected to an arm 36 on the carbureter by means of the link 37. Connected to rotate with the arm 36 is an arm 38 which by means of the adjustable link 39 is connected to an arm 40 carried by the spindle of the choke valve 13. It will be clear that the turning movement of the arm 34 will be transmitted by means of these connections to the choke valve 13. Furthermore as the said arm is connected to the rock shaft 25, when the hand device is moved to set the throttle valve in slightly open position, the choke valve will also be operated but in a closing or opposite direction to the throttle valve. An additional means is provided for operating the choke valve which may be manipulated independently of the rest of the controlling apparatus. This auxiliary or independent means consists of a rod 41 projecting at the front of the vehicle and having its inner end connected to one arm of a rocker 42, the other arm of which by means of a link 43 is connected to an arm 44 rotatably connected to the arm 36. It will be observed that when the rod 41 is pulled toward the left as viewed in Fig. 2, the choke valve will be moved in a closing direction. This operation of the choke valve will also turn the arm 34 but as this arm is yieldingly connected to the rock shaft 25 and the rock shaft is held against movement by the locking means for the hand lever 29, it will be apparent that the arm 34 may move relative to the shaft 25 and the position of the throttle valve will not be altered in any manner by the said operation of the choke valve.

Although a particular form of carbureter is shown in the drawings, it will be understood that the invention is not limited to use in connection with any particular type of carbureter. Furthermore, although a specific embodiment of the invention has been described it is apparent that many of the details may be varied without departing from the spirit thereof.

Having thus described my invention, what I claim and desire to secure by Letters Patent is:

1. In a hydrocarbon engine, in combination with a carbureter having a throttle valve and a choke valve, means for operating said throttle valve comprising a pedal, spring means normally closing said throttle valve, and auxiliary means operative on said pedal to hold it in any desired position, having connections to the choke valve whereby the latter is closed when the auxiliary means is operated to open the throttle valve.

2. The combination with a hydrocarbon motor having a carbureter provided with

a throttle valve, of a pedal positively connected to said valve for operating the latter in one direction, spring means for actuating the valve in the other direction, a hand device operative on said pedal to rock the same to open the valve and hold the latter in such open position, a choke valve for the carbureter, and means actuated by said hand device to adjust said choke valve.

3. In a hydrocarbon engine, in combination, a carbureter having a throttle valve, a pedal positively connected to the valve for operating the latter in one direction, spring means for actuating the valve in the other direction, a hand device operative on said pedal to rock the same to open the valve and hold the latter in such open position, a choke valve for the carbureter, and means actuated by the said hand device to close the choke valve as the throttle valve is opened.

4. In a hydrocarbon engine, in combination, a carbureter having a throttle valve, a pedal positively connected to the valve for operating the latter in one direction, spring means for actuating the valve in the other direction, a hand device operatively on said pedal to rock the same to open the valve and hold the latter in such open position, a choke valve for the carbureter, yielding means actuated by the said hand device to close the choke valve as the throttle valve is opened, and an additional manually operable means for closing the choke valve.

5. The combination with a hydrocarbon motor having a carbureter provided with a throttle valve, means positively connected to the valve for operating the latter, a hand device operative on said means to open said valve and hold it open, a choke valve for the carbureter, and means actuated by said device to adjust said choke valve.

6. In a hydrocarbon engine, in combination, a carbureter having a throttle valve, a pedal positively connected to the valve for operating the latter in one direction, spring means for actuating the valve in the other direction, a rock shaft, means for operating the said shaft and holding it in any position, and a cam on said shaft adapted to act on said pedal.

7. In a hydrocarbon engine, in combination, a carbureter having a throttle valve, a pedal positively connected to the valve for operating the latter in one direction, spring means for actuating the valve in the other direction, a rock shaft, means for operating the said shaft and holding it in any position, a cam on said shaft, and a bolt on said pedal having its end resting on the cam.

8. In a hydrocarbon engine, in combination, a carbureter having a throttle valve, a pedal positively connected to the valve for operating the latter in one direction, spring means for actuating the valve in the other

direction, a rock shaft, means for operating the said shaft and holding it in any position, a choke valve for the carbureter and means whereby rotation of said shaft actuates both 5 the choke valve and pedal.

9. In a hydrocarbon engine, in combination, a carburetor having a throttle valve, a pedal positively connected to the valve for operating the latter in one direction, spring 10 means for actuating the valve in the other direction, a rock shaft, means for operating the said shaft and holding it in any position, a choke valve for the carbureter, a yielding connection between said shaft and latter 15 valve, connections between said shaft and pedal, whereby rotation of said shaft actuates both valves, and means for manually operating said choke valve independently of the throttle valve.

10. In a motor vehicle, in combination, a hydrocarbon motor having a carbureter provided with a throttle valve and a choke 20 valve for controlling the supply of air to the carbureter, a device for controlling the throttle valve including a spring acting to close the same, means to operate the choke valve and means actuated by moving the choke valve in its closing direction only to move the throttle valve in its opening direction 25 whereby the throttle valve may be operated independently of the choke valve when the latter is open.

11. The combination with a hydrocarbon motor having a carbureter provided with

a throttle valve and a choke valve for controlling the supply of air to the carbureter, of means to control the throttle valve, means to control the choke valve, and means operated only by closing the choke valve to open the throttle valve whereby the throttle 40 valve may be operated independently of the choke valve when the latter is open.

12. In a hydrocarbon motor having a carbureter, a valve regulating the supply of combustible mixture from the carbureter to 45 the motor, a choke valve regulating the supply of air to the carbureter, means to operate the mixture valve and means to operate the air valve; the improvement comprising means operated only by the closing movement of the air valve to open the mixture 50 valve.

13. In a hydrocarbon motor having a carbureter, a valve regulating the supply of combustible mixture from the carbureter 55 to the motor, a choke valve regulating the supply of air to the carbureter, means to operate the mixture valve and means to operate the air valve; the improvement comprising a one-way connection between the air 60 valve and the mixture valve whereby the mixture valve is opened by the closing movement of the air valve, but the mixture valve may be operated independently of the air valve when the latter is open.

In testimony whereof I affix my signature.

HAROLD D. CHURCH.
